United States Patent Office

Des. 183,710
Patented Oct. 21, 1958

183,710

HANDBAG OR SIMILAR ARTICLE

Marilyn Blaivas, Lawrence, N. Y.

Application February 5, 1958, Serial No. 49,513

Term of patent 3½ years

(Cl. D87—3)

I claim:
The ornamental design for a hand bag or similar article, substantially as shown.
